(57) **CLAIM**

The ornamental design for a snow ice sensor interface, as shown and described.

DESCRIPTION

FIG. 1 is a front perspective view of a snow ice sensor interface.

FIG. 2 is a rear perspective view of the snow ice sensor interface.

FIG. 3 is a front view of the snow ice sensor interface.

FIG. 4 is a rear view of the snow ice sensor interface.

FIG. 5 is a left side view of the snow ice sensor interface.

FIG. 6 is a right side view of the snow ice sensor interface.

FIG. 7 is a top view of the snow ice sensor interface.

FIG. 8 is a bottom view of the snow ice sensor interface.

FIG. 9 is a front perspective view of a second embodiment of the snow ice sensor interface.

FIG. 10 is a rear perspective view of the second embodiment of the snow ice sensor interface.

FIG. 11 is a front view of the second embodiment of the snow ice sensor interface.

FIG. 12 is a rear view of the second embodiment of the snow ice sensor interface.

FIG. 13 is a left side view of the second embodiment of the snow ice sensor interface.

FIG. 14 is a right side view of the second embodiment of the snow ice sensor interface.

FIG. 15 is a top view of the second embodiment of the snow ice sensor interface; and,

FIG. 16 is a bottom view of the second embodiment of the snow ice sensor interface.

The broken lines in the figures show features of the snow ice sensor interface that form no part of the claimed design.
